UNITED STATES PATENT OFFICE.

HENRY WAMPACH AND JACOB WAMPACH, OF JORDAN, MINNESOTA.

DOOR CONSTRUCTION FOR SILOS.

1,247,186.

Specification of Letters Patent. Patented Nov. 20, 1917.

Application filed April 9, 1917. Serial No. 160,832.

To all whom it may concern:

Be it known that we, HENRY WAMPACH and JACOB WAMPACH, citizens of the United States, residing at Jordan, in the county of Scott and State of Minnesota, have invented certain new and useful Improvements in Door Constructions for Silos; and we do declare the following to be a full, clear, and exact description of the invention, such as will enable others skilled in the art to which it appertains to make and use the same.

This invention relates to silos and more particularly to the door construction and operating mechanism for the same.

An object of the invention is to provide means whereby a silo door may be opened and closed at will.

Another object is to provide means for locking the door in closed position when so desired.

Still another object is to provide means whereby the door may be held fully open or closed or in a plurality of positions.

In the drawings:

Figure 1 is a front elevation in closed position;

Fig. 2 is a front elevation in opened position;

Fig. 3 is a top plan view on the line 3—3 of Fig. 1;

Fig. 4 is a longitudinal sectional view on the line 4—4 of Fig. 1;

Fig. 5 is a side elevation showing the walls in section with the door in open position;

Fig. 6 is a perspective view of the bearing 4; and,

Fig. 7 is a perspective view of the locking plate 14.

The frame 1 is of any suitable size and has a door 2 adapted to fit therein. Positioned near the top of the frame 1 are bearings 3 and 4, through which a shaft 5 passes. One end of the shaft 5 is made smaller as at 6 to permit the handle or lever 7 to pass thereon.

The handle 7 is limitedly pivoted to the shaft 5 by the pin 8.

The shaft 5 carries a substantially U-shaped hanger 9, which is L-shaped in side elevation, and is pivotally fastened at 10 to the door 2, for swinging the door open and closed.

The bearing 4 is substantially C-shaped and has its lower arm formed at its outer end with a hook 11, whereas the upper arm 12 has slots 13 formed therein. A substantially L-shaped plate 14, having a

shoulder 15, is adjustably placed on the arm 12 and is provided with bolts 16 which go through the slots 13 for holding the two members in a plurality of adjustments. The handle 7 will engage the hook or keeper 11 when the door 2 is in open position and will engage the shoulder 15 on the L-shaped plate 14 when the door is closed.

It will be observed that the vertical or central portion of the bearing 4 is bowed outwardly as indicated at 4', it being within this outwardly bowed portion that the shaft 5 is received. The entire bearing 4 is by preference formed of a single piece of metal, stamped into shape, but a casting could well be employed if desired.

A resilient bar 17 is detachably hinged at 18 to one side of the frame 1 and is permitted to tilt as seen in dotted lines in Fig. 1. On the opposite side of the frame 1 is positioned a retaining member 19, having a shoulder forming a cam 20, upon which the bar 17 slides outwardly until it is forced into locked position in said retaining member.

A keeper 21 is attached to the door 2 at about the central point thereof and hook 22 is adjustably connected to the resilient bar 17 by the bolt 23 and is adapted to engage with the keeper 21 to hold the door in closed position.

In operating the device, to open the door, it is only necessary to lift up the spring bar 17 out of engagement with the retaining member (see Fig. 1) and then unfasten the hook 22 from the keeper 21. Then by pulling the handle 7 out of engagement with the shoulder 15 of the L-shaped plate 14, and swinging it down, the door will be caused to be opened by the hanger 9. It is then only necessary to fasten the handle 7 behind the hook 11 to hold the door 2 in open position.

The resilient bar 17 may also be used as a rung of the silo ladder.

From the foregoing description, it will be seen that the door may be readily opened and closed, also that it may be held in a plurality of different positions.

Various changes in the form, proportion and the minor details of construction may be resorted to without departing from the principle or sacrificing any of the advantages of the claimed invention.

We claim as our invention:

1. The combination with a door frame and a door operatively coacting with the

rear side thereof, of a rock shaft journalled adjacent the upper end of the frame, at the front side thereof, a hanger depending from said rock shaft and connected pivotally with 5 said door, an operating handle extending laterally from one end of said rock shaft and pivotally connected therewith for swinging longitudinally thereof, and a pair of keepers positioned adjacent opposite sides 10 of said shaft for coöperation with said handle for locking the shaft against movement when the door is respectively opened and closed.

2. The combination with a door frame 15 and a door operatively coacting with the rear side thereof, of a horizontal rock shaft mounted adjacent the upper end of said frame, at the front side thereof, a hanger carried by said shaft and connected pivotally 20 with said door, an operating handle extending laterally from one end of said shaft and pivoted thereto for swinging longitudinally thereof, a keeper adjacent one side of said shaft for coaction with said handle when 25 the door is in one position, a second keeper adjacent the other side of the shaft for coaction with said handle when the door is in its other position, a horizontal arm extending forwardly from the frame and contacting 30 with said last named keeper, and means connecting this keeper and said arm adjustably.

3. The combination with a door frame and a door operatively associated with the 35 rear side thereof, of a horizontal rock shaft mounted at the front side of said frame, adjacent the upper end thereof, a C-shaped bearing member having its vertical portion secured to said frame and bowed forwardly

to provide a bearing for one end of said shaft, keepers carried by the upper and lower arms of said bearing member, and an operating handle extending laterally from said rock shaft and pivotally connected therewith for swinging longitudinally thereof, said handle coacting with one of said keepers when the door is closed and with the other when said door is opened. 40 45

4. The combination with a door frame and a door operatively associated with the rear side thereof, of a horizontal rock shaft mounted at the front side of said frame, adjacent the upper end thereof, a C-shaped bearing member having its vertical portion secured to said frame and bowed forwardly 50 to provide a bearing for one end of said shaft, one of the horizontal arms of said bearing member having a keeper formed on its free end whereas the other arm is formed with a longitudinal slot, a keeper contacting with said last named arm, a fastener passing through said slot and said last named keeper for securing the latter in adjusted position, and an operating handle extending laterally from said rock shaft and 55 pivotally connected therewith for swinging longitudinally thereof, said handle coacting with one of said keepers when the door is opened and with the other when said door is closed. 60 65 70

In testimony whereof we have hereunto set our hands in the presence of two subscribing witnesses.

HENRY WAMPACH.
JACOB WAMPACH.
